UNITED STATES PATENT OFFICE.

ISAAC M. PEASE, OF CINCINNATI, OHIO, ASSIGNOR TO THE OHIO TRUSS COMPANY, A CORPORATION OF OHIO.

PAD FOR TRUSSES.

Application filed September 29, 1926. Serial No. 138,506.

My invention relates to pads for trusses for the treatment of ruptures and similar troubles.

The principal object of this invention is 5 to provide a pad having a central raised head or bearing portion, and a surrounding friction surface, whereby the pad is arranged to remain in suitable and comfortable adjustment, and also to provide superior features 10 of treatment for the ailments for which such pads are designed.

Further objects of the invention will appear from the following detailed description thereof.

15 In the drawings:

Figure 1 is a front view of a truss pad constructed in accordance with this invention.

Figure 2 is a side elevation of said pad.

20 Figure 3 is a cross-section of said pad.

The numeral 1 indicates a pad constructed of soft or sponge rubber or other similar material. The pad 1 is provided with an 25 undercut groove 2 which forms a central head 3. The undercut is so made as to provide around the head 3 a thin feather edge 4 which is of a readily pliable and resilient nature. The main body of the pad 1 surrounding the head 3 is provided with a 30 roughened or non-skid surface 5. The surface 5 is formed by means of reticulated grooves, as shown in the drawings, or in any other suitable manner.

The pad 1 is secured in the usual manner 35 to a base plate 6 whereby in turn it is secured to a truss supporting member 7.

From the foregoing description, the nature and value of the present invention will be apparent to those skilled in the art to 40 which the same appertains. A truss pad constructed as above described provides, as

will be seen, a head 3 which is adapted to rest in or against the point of rupture, thus amply sustaining the same and more firmly than in the case of the ordinary simple truss 45 pad heretofore in use. Furthermore, by reason of the outward tapering of the head to the feather edge 4, the head is maintained more effectively in the rupture opening than is the case where a head not provided with 50 the feather edge is used, for the reason that the tapering or feather edge is adapted to move with the movement of the body around the rupture opening forming a suction which will serve to maintain the pad effectively 55 in position. In other words, the feather edge is susceptible of a vibratory or fluttering motion during the breathing or other movements of the patient which tends to and does create a suction which forces in- 60 wardly the central portion of the head of the pad. It is thus possible to maintain a pad of the present construction in position with a much lighter and flexible truss spring 65 than is the case with a rigid or uniformly solid pad even where such pad is provided with a head, thus contributing greatly to the comfort and well being of the patient.

Having thus fully described my invention, what I claim as new and desire to secure 70 by Letters Patent is:

1. A pad for trusses, comprising a body, a resilient head over the middle portion of said body, said head tapering outwardly to a thin resilient surrounding edge. 75

2. A pad for trusses, comprising a body, a resilient head over the middle portion of said body, said head tapering outwardly to a thin resilient surrounding edge, and a non-skid surface on said body surrounding said 80 head.

ISAAC M. PEASE.
